BOTTLE CLOSURE

Walter E. Kuenstler, Grantwood, N. J.

Application March 13, 1935, Serial No. 10,770

5 Claims. (Cl. 215—42)

This invention relates to bottle closures and has for its object to provide a closure which is secured to and becomes a part of the bottle and requires destruction before the contents can be removed.

5 When the closure is destroyed, that fact is plainly indicated so that it is impossible for the bottle to be refilled without that fact being clearly apparent.

More particularly, the invention comprises a closure member fitting into the neck of a bottle and being integrally fused thereto and closing the mouth of the same, the closure having a part which must be broken off to permit the contents of the bottle to be removed, which part when broken off, falling into and remaining in the bottle indicates that the bottle has been opened.

In the accompanying drawing, wherein the preferred embodiment of the invention is shown, Fig. 1 is a side view of the upper portion of a bottle provided with the improved closure means; Fig. 2 is a sectional view of the top of a bottle showing the closure member about to be fitted in position; Fig. 3 is a vertical sectional view of the bottle top with closure member in position; Fig. 4 is a vertical sectional view of the structure shown in Fig. 1; Fig. 5 is a sectional view of the top of the bottle showing the closure member being broken to permit the egress of the bottle contents; and Fig. 6 shows a modified structure.

30 In the drawing, 6 indicates the body of a bottle or other similar glass container, provided with the conventional neck portion 7 having a mouth 8, through which the contents 9 of the bottle are poured in the usual manner. The closure member 10 is preferably made of glass or some other similar frangible material and is preferably colored or tinted so that it is visible through the glass of the bottle. The closure member 10 is conical or cup-shaped, and is provided with a

40 body portion 11 fitting into the neck of the bottle and having a laterally extending annular flange 12 at its upper end, which rests upon the upper end of the bottle neck and is fused or integrally united therewith to secure the closure member in position and form it as an actual part of the bottle. At its lower end, the closure member 10 is provided with a ball or similar enlargement 13, joined to the closure member 10 by means of a neck portion 14 constituting a weak point or 45 groove at which the ball 13 can be broken off by downward pressure imposed on it through the cavity 17 of the closure member 10, as clearly shown in Fig. 5.

From the foregoing, the operation of the device 50 will be clearly understood. The closed bottle is

shown in Figs. 1 and 4, where it will be seen that the top of the bottle is covered by the conventional thread-on metal cap 15. This cap, when removed, exposes the closure member, as shown in Fig. 3. The closure member being secured to the top of the bottle neck by being fused or integrally united therewith after the bottle is filled, forms a positive non-leak closure for the bottle. To secure access to the contents 9 of the bottle, a pointed tool 16, such as an ice-pick or other 10 implement, is thrust into the recess or cavity 17 in closure member 10 and forced down upon the ball 13 causing the ball to break off at the neck or weakened portion 14, and fall into the bottle. This provides an outlet opening 18 of lesser diameter than the diameter of the ball, so that the ball cannot pass out of said opening and must remain within the bottle and cannot be removed without destroying the bottle. The ball, when lying loose in the bottle, constitutes an indicator 15 which immediately discloses the fact that the bottle has been opened. If the bottle is refilled, the colored ball lying in the bottom of it, and clearly visible to the purchaser, indicates that the bottle has been used and refilled. Since the 20 closure member must be destroyed in the manner indicated to permit the contents of the bottle to be removed, it is obvious that a refilling of the bottle without the purchaser having knowledge of such fact, cannot be successfully done. 30

In Fig. 6 a modification is shown in which the annular flange 12 at the top of the closure member is omitted and the meeting edges of the bottle top and closure member are fused together. With this arrangement, a minimum of 35 heat is required for the fusing operation. In all other respects the structure is similar to that shown in Figs. 1 to 5 inclusive.

What I claim is:

1. A bottle closure comprising, a frangible 40 member located within the neck of a bottle and integrally attached thereto, said member being weakened adjacent its lower end and having an integrally formed enlarged part on its lower end below said weakened point, whereby the enlarged 45 lower end of said member below said weakened point may be broken off by manual pressure and will fall into the bottle, the size of said enlarged part being greater than the opening formed by its being broken off so as to prevent its removal 50 from the bottle after having been broken off.

2. A bottle closure comprising, a conical hollow frangible member fitting into the neck of a bottle and being fused thereto to seal the bottle mouth, said member having an enlarged ball- 55

shaped lower end and having a break-off groove formed adjacent the ball-shaped lower end whereby downward manual pressure on the ball-shaped lower end will cause it to break off on the line of said groove and fall into the bottle.

3. A bottle closure comprising, a conical frangible member fitting into the neck of a bottle, said member having a laterally extending flange at its upper end fused to the top of the bottle, and provided with an enlargement at its lower end, said member having an annular break-off groove located between the flange and enlargement, the portion of the member where said groove is located being of less diameter than the diameter of the enlargement, whereby said enlargement when broken off on the line of said groove will fall into and remain within the bottle.

4. A bottle closure comprising, a closure member fitting into the neck and closing the mouth of a bottle, said closure member being fused to the bottle neck to form an inseparable portion thereof, said member having an enlarged inner

end attached to the closure member by a neck portion of less diameter than said enlarged inner end, said enlarged end being adapted to be detached from the closure member and form by said detachment an opening of less diameter than the diameter of the enlarged end whereby said end when separated will fall into and cannot be removed from within the bottle.

5. A bottle closure comprising a closure member fitting into the neck of a bottle and fused thereto to form an integral part of the neck, said member having an attached inner end portion adapted to be separated from it in such a way as to cause said part to fall into the bottle, said end portion being connected to the closure member by a neck portion of less diameter than the closure member and the end portion whereby the separation of said end portion from the closure member forms an opening too small to permit the passage through it of the separated end portion.
